UNITED STATES PATENT OFFICE.

HENRY W. HIRSCHFELD, OF MERIDEN, CONNECTICUT, ASSIGNOR TO THE MERIDEN BRITANNIA COMPANY, OF SAME PLACE.

DESIGN FOR A SPOON OR FORK HANDLE.

SPECIFICATION forming part of Design No. 12,541, dated October 25, 1881.

Application filed September 24, 1881. Term of patent 7 years.

To all whom it may concern:

Be it known that I, HENRY W. HIRSCHFELD, of Meriden, in the county of New Haven and State of Connecticut, have invented a new Design for a Spoon or Fork Handle; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handles of spoons, forks, and like articles of table-service, the design relating specially to the ornamentation of the handle.

In shape the handle starts from the bowl, the sides parallel to the central circular boss, *a*. From this boss the handle gradually expands, the sides being straight to the end, where it terminates in segment shape. At the upper end is a section inclosed by a bead around the edge, and with a transverse bar, *b*, across the face. This section represents a ground of basket-work on which is a branch representing fruit and leaves. Below this transverse bar is a plain panel surrounded by a small bead inside the edge bead, its upper end segment-shaped, corresponding to the end of the handle. Midway between the boss *a* and the transverse bar *b* is a rose ornament, *d*, down to which the plain panel extends. Below the rose and toward the boss the surface is reeded. On the surface of the handle, below the boss *a* and extending down to the spoon, is a series of

small rose ornaments forming a line of such ornaments up through the center of that part of the handle. 35

The ornamentation of the lower or shank part of the handle may be omitted, as may also the rose *d*. 40

The ornamentation of the tip above the bar *b* may be applied to handles having a different ornamentation below. I therefore do not limit my invention to the combination of ornamentation from end to end of the handle; but 45

What I do claim is—

1. The design for the ornamentation of spoon and fork handles, consisting of the basket-ground with the representation of a branch lying thereon, as shown in the accompanying 50 illustration.

2. The design for spoon and fork handles, consisting of the series of rose ornaments on the face of the lower or shank part of the handle, as shown in the accompanying illustration. 55

3. The design for spoon and fork handles, consisting of the representation of the basket-ground at the tip with branch of fruit lying thereon, the rose ornament *d* on the face, with 40 plain panel above and reeded surface below, substantially as shown in the accompanying illustration.

HENRY W. HIRSCHFELD.
